Primary Examiner — Catherine S Posthauer*Assistant Examiner* — Alison M Ofstun(74) *Attorney, Agent, or Firm* — Michael Best & Friedrich, LLP(57) **CLAIM**

The ornamental design for a power box, as shown and described.

DESCRIPTION

FIG. 1 is a perspective view of a power box, showing our new design.

FIG. 2 is a first end view of the power box of FIG. 1.

FIG. 3 is a second end view of the power box of FIG. 1.

FIG. 4 is a first side elevation view of the power box of FIG. 1.

FIG. 5 is a second side elevation view of the power box of FIG. 1.

FIG. 6 is a first plan view of the power box of FIG. 1; and, FIG. 7 is a second plan view of the power box of FIG. 1. The elements shown in broken lines are included for the purposes of illustrating portions of the power box that form no part of the claimed design.

1 Claim, 5 Drawing Sheets(56)
